United States Patent Office.

ALEXANDER WEMYSS, OF PHILADELPHIA, PENNSYLVANIA, ASSIGNOR TO STUART, PETERSON, AND COMPANY.

Design No. 3,468, dated April 27, 1869.

DESIGN FOR A STOVE.

The Schedule referred to in these Letters Patent and making part of the same.

To all whom it may concern:

Be it known that I, ALEXANDER WEMYSS, of Philadelphia, county of Philadelphia, State of Pennsylvania, have originated a new Design for "Sunnyside" Stove; and do hereby declare that the accompanying drawing, and following explanation thereof, form a full, clear, and exact description of the said design.

In the drawing, the figure represents the fire-place stove in perspective.

A represents the plate, which is fitted against the wall, and which encloses part of the stove.

This plate is arched at the top, where it has a central ornament, *a*, and it has on each side, near the bottom, a scrolled and foliated ornament, *b*.

B is the hearth-plate, having short columns, *d*, supporting a curved fender, *e*, each end of which meets the plate A, where the latter has an ornamental boss, *f*.

The stove has, on the top, an ornamental latticed cover, D, below which the portion E of the stove has the ornament clearly illustrated in the drawing.

The main body of the stove is surmounted with a plate, G, with ornamental edging, and on this plate are the two conical ornamented caps F.

The body of the stove, below the plate G, has the oval mica frames H, and is otherwise ornamented, as shown, and the base of the stove has ornamental annular plates, and other devices, too clearly illustrated to need description.

I claim—

The design for a fire-place stove, substantially as described and illustrated in and by the accompanying drawing.

In testimony whereof, I have signed my name to this specification, in the presence of two subscribing witnesses.

ALEXANDER WEMYSS.
